UNITED STATES PATENT OFFICE.

GEORGE W. PERO, OF WEST NEW BRIGHTON, NEW YORK.

SASH-CORD GUIDE.

SPECIFICATION forming part of Letters Patent No. 298,496, dated May 13, 1884.

Application filed January 21, 1884. (No model.)

To all whom it may concern:

Be it known that I, GEORGE W. PERO, of West New Brighton, in the county of Richmond and State of New York, have invented 5 a new and useful Improvement in Sash-Pulley Fastenings; and the following is declared to be a description of the same.

Sash-pulleys are generally secured in place by screws, a mortise being carefully made in 10 the window-sash or other place and the pulley fitted therein. This operation requires care and accuracy, and takes considerable time.

The object of my present invention is the 15 construction of a sash-pulley that is simple, requiring no screws, and can be quickly secured in place in a simple mortise.

My invention consists in combining with the 20 ordinary sash-pulley, penetrating points or 25 prongs upon the lower end of the case, or the end that enters the lower part of the mortise, and a turn-button in the upper end having a penetrating edge, and a head by which it may be partially revolved to force the end into the 25 wood and hold the pulley-case in place.

In the drawings, Figure 1 is a section of a 30 sash and elevation of the sash-pulley and its case. Fig. 2 is a face view of the pulley, and Fig. 3 is a rear view of the pulley.

The sash-pulley is composed of the face *a*, 35 side walls, *b*, top *c*, and bottom *d*, forming the case, within which is the wheel *e*, and as these parts are of well-known form they do not need further description. Upon the lower part, *d*, of the case are the penetrating points or prongs *f*. One, two, or more of these prongs may be used, as desired, and they are preferably cast with, and as part of the sash-pulley. A hole is provided in the upper part of the face *a*,

and in this hole is placed the head and stem 40 *g*, and the turn-button *h* is riveted or otherwise secured to the said stem at the back of the face *a*, and the edge *i* of said turn-button *h* is beveled and sharpened, as shown in Fig. 1.

To set this sash-pulley a simple mortise is 45 cut in the wood of the sash, corresponding in size to the face *a*, the lower part of the pulley-case is set in the mortise, and the points *f* driven into the wood until the lower edge of 50 the face *a* rests upon the wood of the sash. The pulley is then pushed into the mortise until its face *a* is flush with the surrounding 55 surface of wood. The head and stem *g* and button *h* are now given a half-turn by a screw-driver, which causes the point *i* to embed itself into the wood, and the sash-pulley 60 is thereby secured in place. The turn-button *h* should be turned down, as shown in Fig. 3, while the sash-pulley is being fitted to place. 65

I claim as my invention—

A sash-pulley case having projections *f* at 70 one end adapted to being driven into the wood-work of the window-frame, in combination with a turn-button applied near the other end of the case, the stem of the turn-button passing through the case and terminating with a slotted head, whereby said turn-button may be partially revolved to force the beveled end into the wood of the window-frame, substantially as set forth.

Signed by me this 16th day of January, A. D. 1884.

GEORGE W. PERO.
